COMBINED HOUSING, DEFLECTOR AND MOTOR SHROUD ARRANGEMENT FOR A ROTARY LAWNMOWER

Larry M. Cognata, Nashville, Tenn., assignor to The Murray Ohio Manufacturing Co., Nashville, Tenn.

Filed Jan. 19, 1973, Ser. No. 324,969

Term of patent 14 years

Int. Cl. D15—03
U.S. Cl. D40—1 B

Fig 1

Fig. 2

Fig. 3

Fig. 4

Fig. 5

Fig. 6

Fig. 7

Fig. 8

FIG. 9

FIG. 10

FIG. 1 is a view in perspective of a first embodiment of a combined housing, deflector and motor shroud arrangement for a rotary lawnmower showing my new design;

FIG. 2 is a top plan view thereof;

FIG. 3 is a side elevational view thereof;

FIG. 4 is a front elevational view thereof;

FIG. 5 is a rear elevational view thereof;

FIG. 6 is a view in perspective of a second embodiment of a combined housing, deflector and motor shroud arrangement for a rotary lawnmower showing my new design;

FIG. 7 is a top plan view thereof;

FIG. 8 is a side elevational view thereof;

FIG. 9 is a front elevational view thereof; and

FIG. 10 is a rear elevational view thereof.

I claim:

The ornamental design for a combined housing, deflector and motor shroud arrangement for a rotary lawnmower, substantially as shown and described.
